UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,062, dated February 14, 1888.

Application filed January 11, 1888. Serial No. 200,437. Term of patent 3½ years.

To all whom it may concern:

Be it known that I, ELLEN MORAN, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows an overdress and a round walking-skirt. The skirt displays two flat side panels flaring in V fashion over the center of the front gore and passing into the side back seams. The overdress displays a long waterfall back drapery depending in loose folds from its

pointed basque back, short basque fronts that exhibit a narrow V-shaped plastron between surplices that display gathers at the shoulder and lower edges, a pointed girdle ornament 20 outlining the lower edge in front of the drapery, coat-sleeves, and a standing collar.

What I claim as my invention, and desire to secure by Letters Patent, is—

The design for a lady's costume, as shown in 25 the engraved prints accompanying this specification.

ELLEN MORAN.
